UNITED STATES PATENT OFFICE

2,610,799

RAIL SPLICE

Grover I. Titus, Laramie, Wyo.

Application May 23, 1951, Serial No. 227,867

1 Claim. (Cl. 238—263)

2

This invention relates to a rail splice and has as its primary object the provision of an improved splice or splicing device for the temporary or permanent repair of broken railroad rails.

An additional important object of the invention is the provision of a device of this character which may be readily applied to and/or removed from a broken rail with a minimum of effort and difficulty.

A further object of the invention is the provision of such a device which may be utilized for application to rail breaks of varying sizes and extent.

Still another object of the invention is the provision of a device for this purpose which imparts to the rail a strength at least equal to if not greater than, its original inherent strength.

Still another object of the invention is the provision of a device of this character which may be readily carried aboard a locomotive or tender for immediate application by an individual train crew, thus obviating the necessity of calling out a section crew and further obviating potential delay of rail traffic.

Still another object of the invention is the provision of a device of this character which is adapted to ready adjustment as well as application and which, when applied, will retain its position in substantially slip-proof relation regardless of the hammering effected thereon by the passage of rail traffic thereover.

A still further object of the invention is the provision of a device of this character which is sturdy and durable in construction, reliable and efficient in operation and relatively simple and inexpensive to manufacture, assemble and install.

Other objects will in part be obvious and in part be pointed out as the description of the invention proceeds, and shown in the accompanying drawing, wherein there is disclosed a preferred embodiment of this inventive concept.

In the drawing:

Fig. 1 is a side elevational view of one form of this inventive concept as applied to a conventional railroad rail;

Fig. 2 is a fragmentary top plan view of the construction of Fig. 1;

Fig. 3 is an enlarged cross-sectional view taken substantially along the line 3—3 of Fig. 1, as viewed in the direction indicated by the arrows; and

Figure 4 is a fragmentary inner side elevation of one of the joint bars.

Similar reference characters refer to similar parts throughout the several views of the drawing.

Having reference now to the drawing in detail, there is generally indicated at 10 a railroad rail which includes a ball 11, a web 12, and a base 13, all of conventional or known design. Obviously, the rail may be of any conventional weight as desired and the clamping device of the instant invention sized accordingly.

The instant invention is comprised of a pair of joint bars 14, each formed at its top, as indicated at 15, to conform to the lower face of the rail ball 11, and at its bottom 16 to conform to the top surface of the rail base. The bars 14 may be formed of any desired length in order to accommodate breaks of varying dimensions and are each provided with a series of spaced dimples 17 unilaterally aligned for the reception of the extremity 18 of a screw or bolt 19, carried by a clamp generally indicated at 20 and to be more fully described hereinafter.

The inner surface of each of joint bars 14 is provided with a series of substantially vertical teeth or serrations 21 for the purpose of precluding any possible slippage of the device after its application to the rail. It is to be noted that the bars 14 are so designed and dimensioned as to fit snugly between the bottom of the rail ball and the top of the rail base, and abut securely against the top of the web 12 of the rail.

Referring now to the clamps 20, it will be seen, as best shown in Fig. 3, that each is of substantially U-shaped configuration including a base 22 and a pair of spaced upwardly extending opposite arms 23, each of which latter is provided with a threaded aperture 24 through which the screws 19 are adapted to extend. Each of screws 19 is provided with a head 25 to facilitate the application of a wrench or the like thereto. It should also be pointed out that the point of the screws 19 is preferably of conical configuration, as shown at 18, to facilitate accurate engagement with the dimples 17 in joint bars 14 previously described.

In the use and application of the device, one of bars 14 is positioned on either side of rail 10 extending across the break 26 (see Fig. 1) and suitable depressions dug beneath the rail between adjacent ties to permit the insertion of one or more of clamping members 20 on either side of the break. These members are then suitably spaced in accordance with the dimen-

sions of the break and the screws 19 tightened, the points 18 thereof engaging in the nearest adjacent dimple 17. Thus, the clamps 20 may be readily applied at desired positions, regardless of the dimensions of the break.

It is further to be noted that each of the joint bars 14 is provided at a point adjacent its juxtaposition to the rail ball with an elongated arcuate recess or depression 21 to accommodate the wheel flange of any railroad vehicle passing thereover.

Any suitable means, such as a tie wire or lock wire 30 extending between the heads 25 of bolts 19 may be provided for precluding loosening of the bolts under heavy traffic. Correspondingly, lock washers 31 may also be provided on each individual bolt if desired or if found practical. It is to be understood that such lock washers and/or lock wires are optional and only to be utilized when and if necessary to the effective functioning of the construction.

It will now be seen that there is herein provided an improved rail splice which may be readily applied to a broken rail with a minimum of difficulty and effort and further applied by a train crew without the necessity of calling out a section gang, and which further will be of sufficient strength firmly to hold a broken rail in juxtaposed relation to permit the passage of the heaviest of traffic thereover and which will retain the rail in such position firmly and against slippage for an indefinite period of time, regardless of the volume of traffic which may be passed over such rail.

It will also be seen that there is herein provided a rail clamp which accomplishes all of the objects of this invention, and others, including many advantages of extreme practical utility and commercial importance.

As various embodiments may be made of this inventive concept, and as various modifications may be made in the embodiment hereinbefore shown and described, it is to be understood that all matter herein is to be interpreted merely as illustrative and not in a limiting sense.

I claim:

A temporary splice for abutting rails comprising a pair of elongated joint bars having inwardly convergent upper and lower edges wedgingly engageable between the lower side of the rail head and the upper side of the base flange of the rail, the inner faces of said bars bearing substantially against the opposite faces of the rail web, the outer side of each bar having a plurality of longitudinally spaced apart recesses, a pair of U-shaped clamps having the bights thereof extending transversely of and beneath the base flanges of the rail with the legs of the clamps upright and confronting the outer faces of the bars, said clamps being positionable spaced from the abutting ends of the rails, and lock bolts threaded through the legs of the clamps and each one of said lock bolts engaging at its inner end in any one of a selected recess, said bolts tightly holding said bars against the rails;

GROVER I. TITUS.
